UNITED STATES PATENT OFFICE.

WILLIAM C. LAUGHLIN, OF NEW YORK, N. Y., ASSIGNOR TO LAUGHLIN FILTER CORPORATION, OF NEW YORK, N. Y., A CORPORATION OF DELAWARE.

CENTRIFUGAL SEPARATOR.

Application filed June 2, 1925. Serial No. 34,301.

To all whom it may concern:

Be it known that I, WILLIAM C. LAUGHLIN, a citizen of the United States, residing at New York, in the county of New York and State of New York, have invented certain new and useful Improvements in Centrifugal Separators, of which the following is a specification.

This invention relates to the separation of materials by centrifugal action and particularly the separation of solids from liquids.

Special objects of the invention are to effect continuous automatic separation with a minimum expenditure of energy, rapidly and as thoroughly as may be required and with relatively simple, entirely practical apparatus.

The foregoing and other objects are attained by certain novel features of construction, combinations and relations of parts, hereinafter referred to in the specification and illustrated in the drawings accompanying and forming part of such specification.

The drawings illustrate the invention as embodied in practical commercial form, with some modifications and it is to be understood that further modifications in structure may be made without departure from the spirit and scope of the invention as hereinafter defined and broadly claimed.

Figure 1 is a side elevation of the complete apparatus.

Figure 2 is a broken plan of one of the transmission gear sets by which differential rotation of the parts is effected.

Figure 3 is an enlarged vertical sectional view of the main portion of the machine shown in Figure 1.

Figure 4 is a transverse sectional view of the separator as taken on substantially the plane of line 4—4 of Figure 3.

Figure 5 is a perspective view of one of the scrapers for clearing the ports and withdrawing the separated solid matter.

Figure 6 is a further enlarged broken sectional view as on the line 6—6 of Figure 4, illustrating particularly the relation of the scraper to the other parts.

Figure 7 is a transverse sectional view through the central liquid discharge portion of the machine as on substantially the plane of line 7—7 of Figure 3.

Figures 8, 9 and 10 are broken longitudi-

nal sectional views illustrating some modifications in the structure and operation of the separator.

In the general view, Figure 1, the rotating casing or "bowl" of the centrifugal is indicated at 1 carried by a shaft 2 journaled in suitable bearings in the gear casings 3 and 4, mounted at opposite sides of the casing on a base 5. The material to be treated is shown as fed from tanks 6 by suitable piping 7 into one end of the shaft, which latter for driving purposes is equipped with a sprocket gear 8. A "water box" 9 is shown surrounding the central portion of the casing for taking off the liquid matter and the solid matter is taken off from the annular discharge throats 10, 11 at the ends of the casing, the removal of such solids being facilitated by scoops 12 positioned to receive and carry off such solids.

The supply end of the shafting is shown in Figure 3 as having a bore 13 terminating in radial ports or passages 14. These ports open into an annular distributing chamber 15 which at its outer periphery is in communication by an annular port 16 with the primary separating chamber 17. The front wall 18 of this separating chamber is shown as of conical form and as having the discharge mouth 10 provided at the center of the same.

The partition 19 defining the rearward wall of the first separating chamber provides with the companion wall 18, an annular passage 21 converging toward the center and terminating in inwardly inclined ports 22 opening into an annular chamber 23.

Outwardly inclined ports 24 located at greater radial distances from the center than the ports 22 open from the innermost annular chamber 23 into an outwardly divergent annular channel 25 provided between the walls 26, and opening at the periphery of the bowl into the final separating chamber 27. The outer wall 28 of this final separating chamber is shown as of conical form similar to the other end wall 18 and as having the secondary discharge mouth 11 provided at the center of the same. An annular port 29 provides a way from the last separating chamber to a liquid collecting chamber 30 which is in communication, by way of inclined tubes 31, with an outside collecting chamber 32 having nozzles 33 operating in

the V channel 34 of the water box, said channel having ports 35 opening from this gutter into the interior of the box. The liquid is shown as taken off from the bottom of the water box by piping at 36.

By the flow described the separation is started at the point of entry and is continued substantially up to the point of discharge. The divergent conical wall 37 outlining the inner collecting chamber 15, by reason of its flare acts as a distributing and separating surface, accelerating the flow of the solids through the annular discharge 16. Further acceleration is produced by the outward flow over the flange or partition 19 in the primary separating chamber 17 and concentration of the solids in this chamber is effected by the collection of the solids against the outer cylindrical confining wall 38. With the bulk of the solids removed, the liquid contents flow readily through the convergent annular channel 21. The ports 22 at the inner end of this channel slow up this flow sufficiently to permit entrained solid matter, not taken in the first chamber, to be again subjected to centrifugal action and so be withdrawn into the outer annular portion of that chamber. From the inner collecting chamber 23 the fluid passes through the flaring channel 25 into the outer peripheral portion of the second separating chamber 27. The flow of liquid from this last chamber through the annular channel 29 into the inner collecting chamber 30 is sufficiently retarded to enable finer solids which may yet be entrained at this time to be subjected to the centrifugal action enough to force the same outward into the main body of collected matter. The rate of rotation will largely govern this separating action and usually this is so fixed and the parts are so proportioned that the liquid flowing from inner chamber 30 through tubes 31 into the outer discharge chamber 32 is practically free of solid matter. Thus there may be only clear liquid entering the water box. If, however, only a portion or portions of the contents are to be extracted, the speed of operation and arrangement of parts will be governed accordingly.

The solids are removed continuously and positively, in the present disclosure, through the cooperative action of the casing and a series of guides 40, Figures 4, 5 and 6, inclined from the outer peripheral portion of the separating chamber, inwardly to the annular discharge mouth, said guides being in the form of blades fitting closely the walls of the separating chamber and rotating in the same direction with but at a different rate of speed than the casing. These guides are shown as projecting substantially tangentially from the face of a flange 41 carried by a sleeve 42 journaled to rotate freely on the supporting shaft.

The differential rotation of this sleeve is effected in the illustration by the gearing shown particularly in Figures 2 and 3 and involving herringbone gears 43 on the outer end of the sleeve engaged by similar gears 44 on shaft 45, which latter carries herringbone gears 46 engaged by like gears 47 on the main shaft. As a set of the guide blades is provided in each of the main separating chambers in the present disclosure, one of these differential gear transmissions is provided at each end of the main shaft, indicated in Figure 1 at 3 and 4.

The differential transmissions are so designed and operated in the present disclosure to drive the inwardly inclined guides at a slower rate of speed than the casing, creating an "overrunning" effect of the casing which causes the separating solid matter to crowd against the rear faces of the guides and be thereby deflected inwardly toward the discharge mouth, as indicated by the arrows in Figure 4.

The fitting of the guides to the inner walls of the separating chambers and their rotation at different speed from the separating chambers causes them to act as scrapers for continuously clearing the walls of the chamber. This effect is utilized to keep the annular port 16 clear by providing one or more of the blades with a laterally projecting lug 48 operating in said port and in similar fashion, the outer portion of the channel 21 at the back of the separating chamber is kept clear by annular projecting blades 49 operating in such space.

The scraping blades 49 are shown made as separate elements removably bolted at 50 to lugs 51 on the forward sides of the main blades 40 so that they can be readily removed or replaced and so that they are positioned where they do not interrupt the inward travel of the solids along the rearward faces of the guides. This forward displacement of the scrapers 49 and the forward inclination at which they are set provides outwardly inclined passages 52 for directing lighter solids in the outer end of channel 21 outwardly into the main separating chamber in advance of the main guides, as indicated Figure 4, so that said supplemental blades materially assist in returning entrained solids to the mass of solids collecting in the main chamber.

One of the simple and practical methods of constructing the bowl with its various passages and partitions is shown in detail in Figure 3 where the cylindrical body or barrel of the casing is shown carried by an intermediate web made up of two wide flanges 53, 54 connected at their rims to the cylindrical shell portions 38, 55 and provided at their centers with hubs 56, 57 keyed at 72 on an enlarged section 58 of the shaft. The inclined outer walls of the chambers 15, 30

and the annular partitions 19, 26 are shown carried by the flanges 59, 60 engaged over the hubs 56, 57 and secured by the through bolts 61. Additional bolts 62 secure the web flanges together at a point inside the peripheral discharge chamber 32 and bolts 63 secure the outer flanges 64, 65 in which the discharge nozzles 33 are formed. The web flanges are therefore secured together at the center, at intermediate points and also at the rim.

The annular walls which form the ends of the chambers 15, 30 are shown in the form of flanges 66, 67, engaged on screw threaded shoulders 68 at the ends of the enlarged shaft section, serving as additional means for binding the structure together. The end heads 18, 28 in which the discharge throats are formed are shown as bolted to the ends of the cylindrical shell sections by the rows of fastenings at 69. This provides a suitable, balanced structure which can be rotated safely at the speed necessary for centrifugal action.

25 The sleeve or tubular shafting carrying the solids removing blades is shown made in sections connected by flanged joints at 70.

Various modifications coming within the scope of the invention may be made to adapt 30 the structure to many purposes or to the handling of different materials. Thus instead of admitting the fluid over the face of the distributing flange 19 as in Figure 3, the mixture may be admitted in back of such 35 flange as indicated in Figure 8, said flange being here designated 19^a and the inner chamber 15 being shown as opening directly into the rearward portion of the separating chamber 17 by an annular radially extensive 40 channel 71. This arrangement permits the lighter substances to reverse and flow inwardly through the channel 21^a without having first to pass outward to the rim of the separating chamber as in the first form.

45 With the structure modified as in Figure 9, the inner central chamber 23^a is made a receiving chamber with the supply ports 14^a opening directly thereinto and from this chamber the flow divides, passing outwardly 50 through ports 22^a, 24^a and channels 21^a, 25^a directly into the separating chambers 17^a, 27^a. In this case the side chambers 15^a, 30^a are collecting chambers for the liquid which enters by the annular ports 16^a, 29^a flowing 55 from such chambers by tubes 31^a into the discharge chamber 32.

Figure 10 illustrates a structural modification in which the material is entered from both ends of the shafting and in which the 60 action in both separating chambers is the same. Here the feed channel from the opposite end of the shaft is designated 13^a and since the action at both sides is the same as in Figure 8, to the inner chamber 23, similar 65 reference characters have been used. In this

case the central chamber 23 becomes a receiver for the liquid from both separating chambers and discharges by ports 72 directly into the outer discharge chamber 32.

The action in all forms of the invention is 70 rapid, continuous and unimpeded so that the machine is of high efficiency and has a greater output as compared to other machines in this class. The discharge of the heavier or solid materials from both ends of 75 the machine and the lighter or liquid material from the intermediate peripheral portion increases the capacity of the machine and separates the liquids from the solids so that any disposition may be made of the 80 same. By discharging from opposite ends, a selective separation may be effected, the heavier grade solids being taken off at the first end of the machine and the lighter grade solids being discharged at the opposite 85 end. The inclined guides rotating concentrically within the separating chambers but at reduced speed, assist in the separating action and through their crowding effect on the material, aid in compacting and 90 drying the material on its way to the discharge throats.

What is claimed is:

1. In centrifugal apparatus, a rotary casing having concentric discharge throats at 95 opposite ends of the same and a peripheral discharge intermediate said ends, a collector surrounding said peripheral discharge and supply means discharging into the casing.

2. In centrifugal apparatus, a rotary casing having centrifugal separating chambers in opposite end portions of the same, said chambers provided with annular discharge throats, the casing having a peripheral discharge intermediate the end chambers and 100 provided with flow passages from said end separating chambers to said intermediate discharge.

3. In centrifugal apparatus, a rotary casing having independently discharging separating chambers in the opposite end portions of the same, a discharge chamber intermediate said end chambers and flow passages from said separating chambers to said intermediate discharge chamber. 110

4. In centrifugal apparatus, a rotary casing having independently discharging separating chambers in the opposite end portions of the same, a discharge chamber intermediate said end chambers and flow passages from said separating chambers to said intermediate discharge chamber, including 120 an annular collecting chamber in communication with both separating chambers.

5. In centrifugal apparatus, a rotary casing having separating chambers in the opposite end portions of the same provided with discharge throats, annular chambers of less diameter than the separating chambers in communication with said separating 125 130

- chambers, a collecting chamber intermediate said annular chambers, a peripheral discharge chamber about said collecting chamber and flow passages establishing communication between said chambers.
6. In centrifugal apparatus, a rotary casing having separating chambers in the opposite end portions of the same provided with discharge throats, annular chambers of less diameter than the separating chambers in communication with said separating chambers, a collecting chamber intermediate said annular chambers, a peripheral discharge chamber about said collecting chamber and flow passages establishing communication between said chambers, including convergent annular channels extending from the separating chambers to the collecting chamber.
7. In centrifugal apparatus, a rotary casing having separated chambers in the opposite end portions of the same provided with discharge throats, annular chambers of less diameter than the separating chambers in communication with said separating chambers, a collecting chamber intermediate said annular chambers, a peripheral discharge chamber about said collecting chamber and flow passages establishing communication between said chambers, including convergent annular channels extending from the separating chambers to the collecting chamber, with flow reducing ports at the inner ends of said channels.
8. In centrifugal apparatus, a shaft having a supply passage terminating in a discharge port or ports, a casing mounted on said shaft having a receiving chamber around said port or ports, separating chambers in said casing provided with discharge orifices at opposite ends of the casing and flow passages in the casing providing communication between the receiving chamber and separating chambers.
9. In centrifugal apparatus, a shaft having a supply passage terminating in a discharge port or ports, a casing mounted on said shaft having a receiving chamber around said port or ports, separating chambers in said casing provided with discharge orifices at opposite ends of the casing, flow passages in the casing providing communication between the receiving chamber and separating chambers and a discharge chamber in the casing intermediate the separating chambers, in communication with the latter and having a discharge port or ports at the periphery of the casing.
10. In centrifugal apparatus, a shaft having a supply passage terminating in a discharge port or ports, a casing mounted on said shaft having a receiving chamber around said port or ports, separating chambers in said casing provided with discharge orifices at opposite ends of the casing, flow passages in the casing providing communication between the receiving chamber and separating chambers and a discharge chamber in the casing intermediate the separating chambers, a discharge chamber in the casing intermediate the separating chambers, in communication with the latter and having a discharge port or ports at the periphery of the casing and having a discharge port or ports at the periphery of the casing and an annular collecting chamber surrounding the intermediate portion of the casing and having a communicating discharge receiving trough surrounding the peripheral discharge port or ports of the casing.
11. In centrifugal apparatus, a shaft, a casing having an intermediate web supporting the same on the shaft and forming a partition defining separating chambers in the opposite end portions of the casing, said casing having end walls with concentric orifices about the shaft and defining discharge mouths for the separating chambers.
12. In centrifugal apparatus, a shaft, a casing having an intermediate web supporting the same on the shaft and forming a partition defining separating chambers in the opposite end portions of the casing, said casing having end walls with concentric orifices about the shaft and defining discharge mouths for the separating chambers, said web further defining an annular discharge chamber at the peripheral portion of the casing between the two end separating chambers.
13. In centrifugal apparatus, a shaft, hub sections engaged in abutting relation on said shaft and provided with flanges defining between them an annular chamber and carrying peripheral walls, end plates secured to said peripheral walls provided with discharge throats surrounding the shaft and forming in conjunction with the peripheral walls and hub flanges, centrifugal separating chambers.
14. In centrifugal apparatus, a shaft, hub sections engaged in abutting relation on said shaft and provided with flanges defining between them an annular chamber and carrying peripheral walls, end plates secured to said peripheral walls provided with discharge throats surrounding the shaft and forming in conjunction with the peripheral walls and hub flanges, centrifugal separating chambers and flanges engaged on the hub sections and forming in conjunction with the hub flanges, annular passages open to the separating chambers.
15. In centrifugal apparatus, a shaft, hub sections engaged in abutting relation on said shaft and provided with flanges defining between them an annular chamber and carrying peripheral walls, end plates secured to said peripheral walls provided with discharge throats surrounding the shaft and forming in conjunction with the peripheral walls and hub flanges, centrifugal separating chambers, flanges engaged on the hub

- sections and forming in conjunction with the hub flanges, annular passages open to the separating chambers and flanges at the ends of the hubs providing additional channels 5 in communication with the separating chambers.
16. In centrifugal apparatus, a shaft having an enlarged section with screw threaded shouldered portions at opposite ends of the same, hubs engaged on said enlarged shaft section having flanges carrying casing walls and flanges engaged on the screw threaded portions of the shaft at the ends of the hubs and forming partitions within the casing so formed.
17. In centrifugal apparatus, a shaft having an enlarged section with screw threaded shouldered portions at opposite ends of the same, hubs engaged on said enlarged shaft section having flanges carrying casing walls and flanges engaged on the screw threaded portions of the shaft at the ends of the hubs and forming partitions within the casing so formed and flanges on the hubs at opposite 25 sides of the hub flanges forming in conjunction with the hub flanges and the end flanges, flow passages within the casing.
18. In centrifugal apparatus, a supporting shaft, hub sections on said shaft having flanges cooperating to form inner and outer annular chambers, peripheral walls carried by said flanges, end walls carried by said peripheral walls and forming therewith, in conjunction with the hub flanges, separating 35 chambers, said end walls having discharge throats surrounding the shaft and flow passages providing communication between the inner and outer annular chambers and the separating chambers.
19. In centrifugal apparatus, a supporting shaft, hub sections on said shaft having flanges cooperating to form inner and outer annular chambers, peripheral walls carried by said flanges, end walls carried by said 45 peripheral walls and forming therewith, in conjunction with the hub flanges, separating chambers, said end walls having discharge throats surrounding the shaft, flow passages providing communication between the inner 50 and outer annular chambers and the separating chambers and flanges at the opposite sides of the hub flanges forming annular chambers in communication with the separating chambers.
20. In centrifugal apparatus, a supporting shaft, hub sections on said shaft having flanges cooperating to form inner and outer annular chambers, peripheral walls carried by said flanges, end walls carried by said 55 peripheral walls and forming therewith, in conjunction with the hub flanges, separating chambers, said end walls having discharge throats surrounding the shaft, flow passages providing communication between the inner 60 and outer annular chambers and the separating chambers.
21. In centrifugal apparatus, a supporting shaft, hub sections on said shaft having flanges cooperating to form inner and outer annular chambers, peripheral walls carried by said flanges, end walls carried by said peripheral walls and forming therewith, in conjunction with the hub flanges, separating chambers, said end walls having discharge throats surrounding the shaft, flow passages 70 providing communication between the inner and outer annular chambers and the separating chambers and flanges at the opposite sides of the hub flanges forming annular chambers in communication with the separating chambers, the shaft having a supply passage therein opening into one of said last named annular chambers.
22. In centrifugal apparatus, a supporting shaft, hub sections on said shaft having flanges cooperating to form inner and outer annular chambers, peripheral walls carried by said flanges, end walls carried by said peripheral walls and forming therewith, in conjunction with the hub flanges, separating chambers, said end walls having discharge throats surrounding the shaft, flow passages 75 providing communication between the inner and outer annular chambers and the separating chambers and flanges at the opposite sides of the hub flanges forming annular chambers in communication with the separating chambers, the shaft having a passage therein opening into one of said last named annular chambers, the other of said annular chambers being closed to the shaft passage and provided with discharge 80 outlets opening into the outer annular chamber first mentioned.
23. In centrifugal apparatus, a rotary casing having an annular chamber in the intermediate portion of the same, flaring annular channels extending from said intermediate chamber toward the ends of the casing and separating chambers in the end portions of the casing in communication with said flaring channels.
24. In centrifugal apparatus, a substantially cylindrical casing, heads applied to the ends of said casing and provided with concentric discharge throats, a supply conduit opening into the axial portion of said casing and an internal web intermediate the ends of the casing having a hub for mounting the casing on a shaft.
25. In centrifugal apparatus, a separating drum having separating chambers provided with independent discharge throats at the opposite ends of the drum, flow passages in the intermediate portion of the drum between said separating chambers, a discharge chamber in the intermediate portion of the drum and tubular conduits intercepting the flow passages and opening into said discharge chamber.
26. In centrifugal apparatus, a rotary drum having concentric discharge throats in opposite ends of the same and provided with internal annular partitions defining sepa- 130

rating chambers in the opposite end portions of the drum and inclined flow passages open to said chambers.

27. In centrifugal apparatus, a rotary drum having separating chambers with independent discharge throats in the opposite ends of the drum, an annular discharge chamber in the peripheral portion of the drum intermediate the separating chambers and inclined annular channels open to the separating chambers and convergent toward the intermediate section of the drum. 70

28. In centrifugal apparatus, a rotary drum having separating chambers with independent discharge throats in the opposite ends of the drum, an annular discharge chamber in the peripheral portion of the drum intermediate the separating chambers, inclined annular channels open to the separating chambers and convergent toward the intermediate section of the drum and an annular collecting chamber interposed between said convergent channels and open to the same. 80

29. In centrifugal apparatus, a rotary drum having separating chambers with independent discharge throats in the opposite ends of the drum, an annular discharge chamber in the peripheral portion of the drum intermediate the separating chambers, inclined annular channels open to the separating chambers and convergent toward the intermediate section of the drum, an annular collecting chamber interposed between said convergent channels and open to the same and annular chambers in the intermediate axial portion of the drum open to the end separating chambers. 90

30. In centrifugal apparatus, a rotary drum having separating chambers with independent discharge throats in the opposite ends of the drum, an annular discharge chamber in the peripheral portion of the drum intermediate the separating chambers, inclined annular channels open to the separating chambers and convergent toward the intermediate section of the drum, an annular collecting chamber interposed between said convergent channels and open to the same, annular chambers in the intermediate axial portion of the drum open to the end separating chambers, a shaft supporting the drum and having a supply passage opening into one of said axial annular chambers and connections from the other axial chamber opening into the discharge chamber. 100

31. In centrifugal apparatus, a rotary drum having separating chambers in the end portions of the same provided with independent concentric discharge throats in the opposite ends of the drum and annular chambers in the intermediate axial portion of the drum having annular ports providing communication between said axial chambers and the separating chambers. 110

32. In centrifugal apparatus, a rotary drum having separating chambers in the end portions of the same provided with independent concentric discharge throats in the opposite ends of the drum, annular chambers in the intermediate axial portion of the drum having annular ports providing communication between said axial chambers and the separating chambers and channels providing communication between the end separating chambers extending about said axial chambers. 75

33. In centrifugal apparatus, a rotary drum having separating chambers in the end portions of the same provided with independent concentric discharge throats in the opposite ends of the drum, annular chambers in the intermediate axial portion of the drum having annular ports providing communication between said axial chambers and the separating chambers and an annular discharge chamber in the peripheral portion of the drum in communication with the separating chambers. 85

34. In centrifugal apparatus, a rotary drum having separating chambers in the end portions of the same provided with independent concentric discharge throats in the opposite ends of the drum, annular chambers in the intermediate axial portion of the drum having annular ports providing communication between said axial chambers and the separating chambers, an annular discharge chamber in the peripheral portion of the drum in communication with the separating chambers and flow passages providing communication between the end chambers and located in the intermediate portion of the drum between the outer peripheral discharge chamber and the inner axial chambers. 95

35. In centrifugal apparatus, a rotary drum having a separating chamber with a concentric discharge throat in one end of the drum, an annular discharge chamber in the peripheral portion of the drum and flow passages from the separating chamber to the discharge chamber, including a channel inclined radially inward from the outer peripheral portion of the separating chamber. 110

36. In centrifugal apparatus, a rotary drum having a separating chamber with a concentric discharge throat in one end of the drum, an annular discharge chamber in the peripheral portion of the drum, flow passages from the separating chamber to the discharge chamber, including a channel inclined radially inward from the outer peripheral portion of the separating chamber and an annular receiving chamber in the axial portion of the drum in communication with the separating chamber. 120

37. In centrifugal apparatus, a rotary drum having separating chambers in oppo- 125

- site end portions of the same, shafting supporting said drum, material guides within said chambers and differential gear sets operated by the shafting at opposite ends of 5 the drum for rotating said guides in the same direction as but at a different rate of speed from the drum.
38. In centrifugal apparatus, a rotary drum having discharge throats at opposite 10 ends of the same, means for withdrawing material through said throats and differential gear sets at opposite ends of the drum for rotating said withdrawing means at a different rate of speed than the drum.
39. In centrifugal apparatus, a shaft, a drum mounted on said shaft having a separating chamber in one end provided with a discharge throat surrounding the shaft, a sleeve rotatably engaged on said shaft, 15 guides carried by said sleeve extending into the separating chamber and inclined from the peripheral portion of the same toward the discharge throat and means for rotating the shaft and sleeve at different speeds 20 to effect a travel of matter separated in the chamber along the guides to the discharge throat.
40. In centrifugal apparatus, a shaft, a drum mounted on said shaft having a separating 25 chamber in one end provided with a discharge throat surrounding the shaft, a sleeve rotatably engaged on said shaft, guides carried by said sleeve extending into the separating chamber and inclined from the peripheral portion of the same toward the discharge throat and means for rotating both shaft and sleeve in the same direction but the shaft at greater speed than the sleeve to cause the separated material to 35 be forced by the greater speed of the drum along the inclined guides to the discharge throat.
41. In centrifugal apparatus, a shaft, a drum on said shaft having separating chambers in the opposite end portions of the same with discharge throats surrounding the shaft, sleeves rotatably engaged on the shaft, guides carried by said sleeves extending 45 into the separating chambers and inclined from the peripheral portions of the same toward the discharge throats and means for rotating the drum and the sleeves at different speeds.
42. In centrifugal apparatus, a shaft, a drum on said shaft having separating chambers in the opposite end portions of the same with discharge throats surrounding the shaft, sleeves rotatably engaged on the shaft, guides carried by said sleeves extending 50 into the separating chambers and inclined from the peripheral portions of the same toward the discharge throats and means for rotating the drum and sleeves in the same direction but the drum at greater speed than the sleeves.
43. In centrifugal apparatus, a rotary drum provided with separating chambers in opposite ends of the same, said chambers having concentric discharge throats, material withdrawing means concentrically 55 mounted within the chambers extending from the peripheral portions of said chambers toward the discharge throats and means for rotating the drum and said withdrawing means in the same direction but at different rates of speed. 70
44. In centrifugal apparatus, a shaft, a separating drum mounted on said shaft and provided with discharge throats at opposite ends of the same, material directing 80 means sleeved upon the shaft and operating to direct material in the drum toward the end discharge throats and back-gearing at the opposite ends of the shaft for driving the sleeves of the material directing means 85 in the same direction as the shaft but at reduced speed.
45. In centrifugal apparatus, a separating drum having opposed radially extensive 90 walls and a peripheral wall defining a separating chamber, one of the radially extensive walls having a discharge throat at the axial portion of the same, a material guide within the separating chamber shaped to fit the walls defining said chamber, said 95 guide extending from the peripheral portion toward the discharge throat and means for rotating said guide concentrically with respect to the drum but at a lesser rate of speed. 100
46. In centrifugal apparatus, a shaft, a separating drum mounted on said shaft and having a separating chamber provided with a concentric discharge throat at the axial portion of the same, a sleeve journaled on 105 said shaft, inclined blades on the sleeve fitted to the walls of the separating chamber and extending from the peripheral portion thereof toward the discharge throat and means for driving the sleeve from the shaft in the same direction but at lesser speed than the shaft. 110
47. In centrifugal apparatus, a separating drum having a separating chamber and a supply chamber discharging into the separating chamber through an annular orifice and a separating blade rotating within the separating chamber and having an extension traveling in said annular discharge orifice. 115
48. In centrifugal apparatus, a separating drum having a separating chamber and a supply chamber discharging into the separating chamber through an annular orifice and a separating blade rotating 120 within the separating chamber and having an extension traveling in said annular discharge orifice, said drum further having a flow passage extending from the separating chamber and an inclined extension 125 130

on the separating blade operating in said flow passage.

49. In centrifugal apparatus, a separating drum having an annular separating chamber with an axial discharge throat in one end of the drum and a flow passage at the back of said separating chamber, means for supplying material to the separating chamber including an annular orifice

in one wall of the separating chamber and material guiding and separating blades concentrically rotatable within the separating chamber having extensions projecting into the annular supply orifice and the flow passage aforesaid. 10 15

In testimony whereof I affix my signature.

WILLIAM C. LAUGHLIN.
